UNITED STATES PATENT OFFICE.

ALVAH C. ROEBUCK, OF WOODSTOCK, ILLINOIS.

TYPE-WRITER RIBBON-FEED.

1,189,486.

Specification of Letters Patent. Patented July 4, 1916.

Application filed December 15, 1913. Serial No. 806,700.

To all whom it may concern:

Be it known that I, ALVAH C. ROEBUCK, a citizen of the United States, residing at Woodstock, in the county of McHenry and State of Illinois, have invented certain new and useful Improvements in Type-Writer Ribbon-Feeds, of which the following is a specification.

This invention relates to ribbon feeding devices for typewriters, and more particularly to means for feeding the ribbon upon the return movement of the universal bar.

The principal object of the invention is to provide an improved ribbon feeding device operated from the rock shaft, and to provide a device of this class in which the direction of ribbon feed is easily reversed.

For the attainment of these ends and the accomplishment of other new and useful objects, as will appear, the invention consists in the features of novelty in the construction, combination and arrangement of the several parts generally shown in the accompanying drawings and described in the specification but more particularly pointed out in the appended claims.

In the drawings, Figure 1 is a view of mechanism constructed in accordance with the principles of my invention as viewed on a section line 1—1 of Fig. 2; Fig. 2 is a side elevation, parts being shown in section, of one of the ribbon feeding devices; and Fig. 3 is another view in elevation, some of the parts being omitted and others shown in section, of the mechanism shown by Fig. 1.

Mounted in a typewriter frame, designated generally by the reference numeral 5 at opposite ends thereof, are ribbon spool shafts 6 each provided with a shoulder 7 upon which the ribbon spool is supported, the shoulder being formed with a projection 8 to engage a spool. Spool guards 9 are mounted on the frame surrounding the spool shafts 6 with edges extending upwardly about the periphery of the spool. Mounted on each spool shaft 6 below the top of the frame is a toothed wheel 10.

A rock shaft 11 extends transversely across the machine and rotates freely in bearings 12 forming a part of the frame at the sides thereof. Motion is given to the rock shaft by means of the universal bar 13 which is connected to or formed integral with a frame 14 provided with a perforated ear 15 which oscillates to and fro when the universal bar is struck by the type bars of the

typewriter (not shown). An arm 16 is secured to the rock shaft 11 and carries a pin 17 which extends through the perforation of the ear 15. The pin 17 is of considerable length to permit the longitudinal movement of the rock shaft which constitutes also a shift rod for the feeding mechanism.

A collar 18 is adjustably secured to the shaft 11 adjacent each end thereof to which is secured an arm 19 formed at its free end with an offset portion 20. Pivotaly mounted on a pin 21 secured to the frame 5 is a ratchet pawl 22, one end of which engages the teeth of the wheel 10, the other end of which is in position to be engaged by the offset portion 20 of the arm 19 when the shaft 11 is shifted longitudinally. The pivotal portion of the pawl 22 is formed by bending ears 23 at right angles to the body 70 portion of the pawl and perforating them so that the pin 21 will pass through them. The extremities of these ears 23 are connected by means of a spring 24 with a fixed point or pin 25 secured to the frame so that the spring tends to draw the pawl into engagement with its corresponding toothed wheel 10.

Pivotaly connected to the arm 19 at a point intermediate the extremities thereof 85 is a ratchet pawl 26. This pawl 26 has an outer extremity adapted to engage with the toothed wheel 10 and is formed with an ear 27 to which a spring 28 is attached connecting it with a fixed point, as the pin 25, for drawing the pawl into engagement with the wheel. This pawl 26 preferably extends through a space formed between the other pawl 22 and its pivot pin 21, and it is thereby prevented from lateral movement by engagement with the ears 23 of the pawl 22. The extremity of the pawl 26, which is adjacent the arm 19, is formed with a slot 29 through which the shaft extends, the portion of the pawl below the shaft being 100 formed with a rounded projection 26^a to bear against the arm 13, and the arm being formed with a projection 30 which bears against the pawl 26 above the slot. Between the projections 30 and 26^a is a pivot 105 pin 31 with a knurled nut 32 to fasten the pawl 26 to the arm 13, the pawl being rocked on the projection when the shaft 11 is moved longitudinally, and the pivot pin 31 holding the pawl in proper position.

The two feeding devices at opposite ends of the shaft are spaced so that when the

shaft is moved a certain amount in one direction one of the feeding devices is in engagement with one of the toothed wheels 10 while the other one is moved about the pivot pin 21 out of engagement with its corresponding toothed wheel. When the shaft 11 is moved in the other direction, the offset portion 20 of arm 13 moves the retaining pawl 22 out of engagement with the wheels 10, while the feeding pawl 26 is moved out of engagement through its pivotal action with the main part of arm 13 being rocked by the pivot pin 21 when the rock shaft 11 is moved longitudinally.

In order to limit and guide the movement of the shaft 11 longitudinally it is provided at one end with notches or annular grooves 33. These grooves are properly spaced apart and are engaged by a spring-pressed dog 34 mounted in the frame and held in position by an adjusting device 35. The shaft 11 is also formed with a portion of reduced diameter 36 in which a pin 37 adjustably threaded in the frame and secured in position by a nut 38 is adapted to engage. This pin, by its engagement with the extremities of the portion of reduced size, limits the longitudinal movement of the shaft and prevents its overthrow in either direction. The extremities of the shaft project slightly beyond its bearings 12 at the ends so that it can be readily engaged for movement in either direction by the hand of an operator.

In moving the pawls of either feeding set by the longitudinal movement of the rock shaft the pawl 26 is rocked upon the projections 26^a and 30 which are rounded for this purpose. The projections space the pawl 26 from the adjacent face of the arm, and together with the pivot pin 31, hold the pawl.

In operation the reciprocation of the universal bar causes the oscillation of the rock shaft 11 and it in turn communicates the oscillation by means of one of the pawls 26 to the corresponding toothed wheel 10. The other pawl 22 corresponding thereto acts as a holding pawl to prevent the reversal in rotation of the toothed wheel 10. The reciprocating movement of the pawl 26 causes the rotation of the toothed wheel 10 and the consequent rotation of the ribbon spool. The other ribbon spool is free to rotate at this time because the other feeding device is not in connection with its toothed wheel.

What I claim is:

1. In a typewriter, a reciprocable universal bar frame having a perforated ear, a rotatable and longitudinally movable shaft, an arm connected thereto having a projection of sufficient length to extend through the perforated ear to permit the longitudinal movement of the shaft, and ribbon feeding devices operated by the shaft.

2. In a typewriter ribbon feeding mecha-

nism, the combination of a rotary and longitudinally movable shaft, having a portion of reduced diameter forming shoulders thereon, of ratcheting devices in connection therewith thrown into and out of engagement by the longitudinal movement of the shaft, and fixed means consisting of a lock nut and a threaded stud therefor to engage the shoulders formed by the portion of reduced diameter to limit the movement of the shaft in both directions.

3. In a device of the class described, the combination with a longitudinally movable rock shaft having annular grooves and a portion of reduced diameter forming shoulders therein, of ribbon feeding devices operated by the rock shaft and thrown into and out of engagement by the longitudinal movement thereof, a spring-pressed catch to engage the notches, and a pin adjustable to engage the said shoulders to limit the longitudinal movement of the shaft in either direction.

4. In ribbon feeding mechanism, the combination with a toothed wheel, of a pivoted pawl adapted to engage the wheel at one end, a second pawl adapted to engage the toothed wheel, a rock shaft to which the second pawl is pivoted and by which it is reciprocated, and an arm connected to the rock shaft adapted to engage the free end of the first mentioned pawl when the shaft is moved longitudinally.

5. In a typewriter ribbon feeding mechanism, toothed ratchet wheels, pivotally mounted pawls adapted to engage the ratchet wheels, feeding pawls to rotate the ratchet wheels, a longitudinally movable rock shaft, and arms connected to the rock shaft to which the feeding pawls are pivoted, the arms being adapted to engage the pivotally mounted pawls at their free end to move one of the pivotally mounted pawls and a corresponding feeding pawl into engagement with the ratchet wheel and another pivotally mounted pawl and feeding pawl out of engagement when the rock shaft is moved longitudinally.

6. In typewriter ribbon feeding mechanism, the combination with a toothed ratchet wheel, of a pivotally mounted pawl therefor, a reciprocatory feeding pawl, a longitudinally movable rock shaft, arms having an offset portion connected to the shaft to which the feeding pawl is pivoted, and means for spacing the feeding pawl from the other pawl, the longitudinal movement of the shaft moving the pawls into and out of engagement with the toothed wheel, the offset portion of the arm engaging the free end of the pivoted pawl.

7. In typewriter ribbon feeding mechanism, the combination with a toothed wheel, of a pawl having perforated ears, a pivoted pin passing through the ears, a second pawl

- extending between the ears and between the other pawl and its pivot pin, means tending to draw both pawls in engagement with the wheel, a longitudinally movable rock shaft,
5 an arm connected to the rock shaft having an offset portion to engage the free end of the pivoted pawl when the shaft is moved longitudinally, the second named pawl being pivotally connected to the arm at a point spaced from the shaft and having a slotted portion through which the shaft extends to permit the oscillation of the pawl about its pivot point when the shaft is oscillated, and means to space the pawls apart.
10 8. In ribbon feeding mechanism, the combination with a laterally movable arm, of a feeding pawl pivoted thereto, and means to space the pawl from the arm, upon which means the pawl is rocked when the arm is moved.
9. In ribbon feeding mechanism, the combination with a laterally movable arm, of a

feeding pawl pivoted thereto at the side, and projections on the pawl and arm upon which the arm is rocked when the arm is 25 moved laterally.

10. In ribbon feeding mechanism, the combination with a longitudinally movable rockshaft, of an arm secured thereto having a lateral rounded projection, a pawl having a lateral rounded projection, and a pin to pivot the pawl on the arm, the pin being in line with the projections, the pawl being spaced from the arm by the projections and the lateral movement of the shaft causing 30 35 the pawl to be rocked on the projections.

In testimony whereof I have signed my name to this specification, in the presence of two subscribing witnesses, on this 11th day of December, A. D. 1913.

ALVAH C. ROEBUCK.
